UNITED STATES PATENT OFFICE.

EDWIN HARRIS, OF WASHINGTON, DISTRICT OF COLUMBIA.

DESIGN FOR A SPOON, &c.

SPECIFICATION forming part of Design No. 20,658, dated March 31, 1891.

Application filed March 5, 1891. Serial No. 383,914. Term of patent 3½ years.

To all whom it may concern:

Be it known that I, EDWIN HARRIS, a citizen of the United States, residing at Washington, in the District of Columbia, have invented and produced a new and original Design for Handles for Knives, Forks, and Spoons; and I do hereby declare the following to be a full, clear, and exact description of the same, reference being had to the accompanying drawing, forming a part thereof.

My invention relates to a design for the handles of spoons and similar articles; and it consists in the arrangement and aggroupment of the respective features thereof hereinafter described and claimed.

In the accompanying drawing, wherein is illustrated a front elevation of a spoon embodying my design, A represents a handle, the end of which is enlarged, as at B, and the lower portion being narrowed, as at C, and terminating in an enlargement D, which latter is connected to the spoon-bowl, blade, or fork. The face of the handle is formed into a single panel having a beading around its entire edge, as at E. The upper end of the handle has a crown F. In the enlarged

portion of the handle is placed a vignette or representation of a fanciful view of the public building known as the "President's House," with shrubbery interspersed through the grounds thereof, the center portion of the building having a flag-staff thereon, which projects upwardly to a point at or about the center of the crown, the remaining portion of the crown being occupied by a fanciful configuration, as shown. Below the vignette is a space upon which suitable inscriptions may be placed. The lower portion of the handle is filled in with the fanciful configuration shown.

Having thus described my invention, what I claim as new, and desire to secure by Letters Patent, is—

The design for a spoon, &c., substantially as herein shown and described.

In testimony whereof I affix my signature in presence of two witnesses.

EDWIN HARRIS.
